BRAKE MEANS FOR YARNS

Willis A. Ingalls, Syracuse, N. Y., assignor to
Tompkins Bros. Co., Syracuse, N. Y., a corpora-
tion of New York

Application February 4, 1938, Serial No. 188,763

5 Claims. (Cl. 66—145)

This invention appertains to improvements in
yarn changing or striping attachments for knit-
ting machines, and more especially, to braking
means for effectively stopping the movement of
5 the yarn when the yarn is taken out of the knit-
ting action.

Yarn changing instrumentalities, as applied to
circular spring needle knitting machines and the
like, generally include two or more movable
10 guide fingers through which the yarns to be
knitted are threaded, the movement of the
fingers being preferably pattern-controlled so as
to selectively move the yarns into and out of
operative relation to a stitch wheel which serves
15 to feed the yarns into the needles of the rotary
needle cylinder. I have found that in certain
types of yarns, more especially in the case of
natural or artificial silk yarns, including acetate
yarns, the yarn has a tendency to continue to
20 run through the eyes and guides after its guide
finger has moved away from the stitch wheel to
take the yarn out of the knitting action, this
continued movement being primarily due to the
inertia or momentum of the yarn. As a result
25 of this continued movement of the yarn after
it has been moved away from the stitch wheel,
and even though the over-run is only momentary,
so much slack is produced in the yarn between
the guide fingers and the cutter and clamp in-
30 strumentalities usually associated therewith, that
it frequently happens that the yarn will miss the
stitch wheel when the guide finger is returned to
its position in which the stitch wheel is adapted
to engage the yarn to feed it into the needles, or
35 in other words, in restoring the yarn to the con-
dition of knitting action. Obviously, therefore,
the knitted fabric may be imperfect, and under
some conditions, the yarn changing instrumen-
talities are rendered virtually inoperative. It is
40 to be understood that the same difficulty may also
be encountered in the case of cotton yarns, which
often times vary materially in their properties
and characteristics, all of which has an important
bearing upon the feed of the yarn.

45 It is the principal object of this invention to
overcome the difficulties aforementioned and to
insure a more positive action of the yarn chang-
ing instrumentalities in respect to the presenting
50 of the yarns to the stitch wheel or other device,
as the case may be, which feeds the yarn to the
needles of the knitting machine. To this end, I
provide a brake device which preferably effects a
clamping action upon the yarn when the yarn is
55 taken out of knitting action, the brake being re-

leased when the yarn is restored to knitting
action.

Another object of the invention is to provide a
yarn brake or clamp which is preferably operable
responsive to the operation of the guide finger of
a conventional yarn changing attachment, the
operation of the brake or clamp being such that
the same is rendered effective to immediately stop
the movement of the yarn when the guide finger
is shifted to its idle or non-feeding position, but 10
being rendered ineffective so as to release the
yarn and permit it to move under normal running
conditions incident to movement of the guide
finger to an operative yarn feeding condition.

Other and further objects and advantages of 15
the invention will be hereinafter described, and
the novel features thereof defined by the ap-
pended claims.

In the drawing:

Figure 1 is a view in side elevation of a yarn 20
changing attachment for a circular spring needle
knitting machine, the pattern-controlled cams
which actuate the yarn guide fingers being shown
in broken lines, and the yarn changing attach-
ment having my invention incorporated therein; 25

Figure 2 is a top plan view of the yarn chang-
ing attachment shown in Figure 1.

Like reference characters designate corre-
sponding parts in the figures of the drawing, 30
wherein 1 generally designates one form of yarn
changing or striping attachment which is avail-
able on the market at the present time, and
which is primarily intended for use with circular
spring needle knitting machines. The details of
the knitting machine are immaterial to the pres-
ent invention, and have therefore not been shown
in the drawing. Also, it is to be understood that
my invention is not limited to use with the par-
ticular type of yarn changing attachment shown
in the drawing, since the details may be varied or
modified as desired and without affecting the
basic idea underlying the invention. Accord-
ingly, the construction of the yarn changing in-
strumentalities as shown in the drawing and 40
hereinafter described should be taken as an illus-
trative example only, and not in any sense as a
limitation of the scope of the invention.

As in conventional yarn changing mechanisms,
there are usually provided two or more guide 50
fingers 2, 2', which are pivotally mounted, as at 3,
between spaced standards 4, 4 which form a part
of the frame 5 of the attachment. The pivotal
axis 3 of the guide fingers is preferably inclined
so that the fingers move in inclined planes to- 55

wards and away from the stitch wheel (not shown) which is usually mounted outside of the circle of needles carried by the rotary needle cylinder of the knitting machine, as will be understood by those familiar with the art. According to the construction illustrated in the drawing, the guide finger 2 is in its uppermost position which constitutes the yarn feeding position by reason of the fact that when so positioned, the yarn 6 which is threaded through the eye 7 at the free end of the finger 2, is carried upwardly towards the stitch wheel so as to be engaged by the latter and consequently fed into the needles. The other guide finger 2' is shown in its depressed condition corresponding to the non-feeding position of the yarn 8 which is threaded through the eye 9 at the free extremity of this finger. When the finger 2' is actuated to its depressed position just referred to, the yarn 8 which is guided by this finger is moved away from the stitch wheel, so that the stitch wheel cannot engage the same and therefore cannot feed this yarn into the needles. As the finger 2' reaches its non-feeding depressed condition, the yarn 8 is severed and clamped at a point between the stitch wheel and the needles by means of cutting and clamping instrumentalities, generally designated 10. The stitch wheel is normally positioned intermediate the cutter and clamping device 10 and the guide fingers 2, 2', with its axis disposed somewhat above the uppermost position of the guide fingers so that the yarns are presented by the guide fingers to the lower edge of the stitch wheel when the guide fingers are actuated to yarn feeding position. Thus, when the yarn, such as yarn 8, is taken out of the feeding action, and the yarn is severed and clamped by the device 10, the portion of this yarn which extends between the finger 2' and the device 10 lies below and in spaced relation to the stitch wheel, and remains in such position until the finger 2' is actuated to a yarn feeding position corresponding to the position in which the guide finger 2 is shown in the drawing. As the finger 2' reaches the yarn feeding position, the cutter and clamp device 10 is actuated to release the end of the yarn so that the yarn can be freely drawn through the eye 9 by the feeding action of the stitch wheel, thus corresponding to the condition represented by the yarn 6, which, as shown in the drawing, is disposed in a feeding or running position.

The guide fingers 2, 2' are preferably alternately actuated so that when one finger is depressed to take its yarn out of the knitting action, the other finger is raised to put its yarn into the knitting action, and vice versa. The guide fingers are preferably pattern-controlled by suitable automatically operating instrumentalities, and since the details of these instrumentalities are not material to the present invention, only a brief general description thereof will be given.

The frame 5 of the yarn changing or stiper unit 1 is preferably mounted on an upright stand 11, which is disposed in outwardly spaced relation to the needle circle, the frame being preferably adjustably secured to the stand by a suitable fastening, such as the bolt 12, which extends through the slot 13 in the stand and into the frame 5. When the device is so mounted, the guide fingers 2, 2' are disposed substantially radially respecting the circle of needles carried by the needle cylinder of the knitting machine. Pivotally mounted at 14 between a pair of lugs or bosses 15, 15, are a pair of bell-cranks 16, 16'.

One arm 17 of the crank 16 is operatively connected by a link 18 to the guide finger 2, and the corresponding arm 17' of the crank 16' is operatively connected to the guide finger 2' by a link 18'. Mounted in the frame 5 and freely shiftable axially therein are a pair of push pins 19, 19', the upper extremities of which bear against the lower sides of the respective arms 20 and 20' of the bell cranks 16, 16', and the lower ends of these push pins coact with a notched cam wheel 21 which is rotatably mounted in the frame 5. The notches 22 are so arranged in the upper end of the cam wheel 21 that when one push pin registers with a notch so that its lower end will be received therein, the other push pin will engage the upper end of the cam wheel 21 between two adjacent notches. Tension springs 23, 23' serve to normally rock the respective bell-cranks 16, 16' in a counter-clockwise direction as viewed in Figure 1. Spring 23 has one end secured to a convenient point on the frame 5, as at 24, and its other end secured to a post or pin 25 which projects laterally from the crank arm 17 near the free extremity thereof. Similarly, spring 23' has one end suitably fixed to the frame 5, as at 24', and its other end secured to a post 25' laterally projecting from the crank arm 17' near the free extremity of the latter.

By intermittently rotating the cam wheel 21, the push pins 19, 19' will be alternately raised and lowered, thereby alternately rocking the bell-cranks 16, 16' in opposite directions, which in turn causes the guide fingers 2, 2' to be alternately elevated and depressed. As shown in the drawing, the intermittent motion is imparted to the cam wheel 5 by means of a ratchet wheel 26 which is fixed to the vertical shaft 27, which is rotatably mounted in the frame 5 and to the upper end of which the cam wheel 21 is fixedly secured. A spring pawl (not shown), carried by an arm 28 which is rotatably mounted on the shaft 27 for movement in a horizontal plane, coacts with the ratchet wheel 26 to intermittently rotate the ratchet wheel responsive to swinging movement of the arm 28 in one direction, the arm 28 being normally urged in the opposite direction by a spring 29 having one end connected with the arm and the other end connected to a convenient part of the frame 5, as at 30. Swinging movement is imparted to the arm 28 preferably by means of a pattern controlled cam 31 which is mounted on the rotary needle cylinder of the knitting machine. This cam, according to one well known construction which is in use at the present time, is movable from an operative to an inoperative position and vice versa, respecting the arm 28. When the cam 31 is in its operative position, as shown, it strikes an adjustable extension 28' carried by the free end of the arm 28, thereby imparting a swinging movement to the arm 28 and actuating the ratchet wheel 26 one step. After the cam 31 has swung the arm 28 and actuated the ratchet wheel one step, as just described, continued rotation of the needle cylinder on which the cam is mounted disengages the cam from the extension 28', thereby allowing the arm 28 to return to its normal position under the influence of the spring 29, and conditioning the mechanism for succeeding step-by-step operations as the cam 31 is carried around with the needle cylinder, and until the cam is shifted to an inoperative position.

The cutter and clamping instrumentalities 10 are preferably similarly operated in timed rela-

tion to the guide fingers 2, 2', by means of a second cam 32, also mounted on the rotary needle cylinder, and also preferably movable from operative to inoperative position along with the cam 31. 5 This cam 32 coacts with an adjustable arm 33 carried by a member 34 which is fixedly mounted on a lever arm 35, the lever arm being pivotally connected intermediate its ends to the frame 5, as at 36. One end of the lever arm 35 is connected, as at 37, to one end of a tension spring 38, the opposite end of the spring 38 being connected to a convenient point on the frame 5, as at 39. Adjustably mounted at the opposite end of the lever arm 35, is an upstanding post 40, and 10 a link 41 interconnects the upper end of the post 40 with the movable parts of the cutter and clamp instrumentalities 10, these instrumentalities being suitably supported on the frame 5 by a bracket arm 10'. The spring 38 normally serves to actuate the device 10 to its yarn cutting and clamping position, as illustrated in Figure 1, whereas engagement of the cam 32 with the part 33 during rotation of the needle cylinder actuates the pivotal lever 35 and the parts interconnected therewith so 15 as to open the cutter and clamping device to release one yarn as it is put into knitting action, and to receive the other yarn as it is taken out of the knitting action. The same cutter and clamping instrumentalities 10 serve to alternately coat with both yarns 6 and 8, and the actuation of these instrumentalities continues intermittently as the needle cylinder rotates and responsive to the cam 32 until this cam is moved to inoperative position.

So much of the construction of the yarn changing mechanism and the operation thereof, as above described, is well known, and I will now explain my invention as applied to this mechanism. As shown in the drawing, the yarns 6 and 8 run from a suitable source, generally designated 20 Y, to the yarn changing attachment, and are threaded through eyes 42, 43, respectively, provided in the frame 5 at opposite sides thereof. Each eye is preferably provided with a porcelain bushing 44, so that the yarn will run freely 25 through the eye without engaging any sharp edges which would tend to damage or sever the yarn. From the eyes 42, 43, the yarns extend to the eyes 7 and 9, respectively, of the guide fingers 2, 2'. With some types of yarns and in some 30 types of knitted patterns, it is desirable to apply a tension to the yarn during the feeding or running of the yarn, and to this end, a plurality of horizontally disposed wires 45 are provided in the frame 5, these wires lying substantially transversely to the direction of the feed of the yarn. By running the yarns under and over the wires 45, a light drag or tension is produced on the yarn. This is a running tension and should not be confused with the braking action on the yarn, 35 to which the present invention primarily relates. By varying the threading arrangement of the yarn respecting the wires 45, the running tension on the yarns can be varied, and in some cases, it is not necessary to run the yarn through the wires 40 45 at all. However, where silk yarns and the like are being used, and even though the yarn is threaded through the tension wires 45, the inertia or momentum of the yarn is often times so great as to cause the yarn to continue to run after 45 the yarn has been taken out of the knitting action through depressing its guide finger to disengage the yarn from the stitch wheel. This momentum results in the production of considerable slack in the yarn, and this slack may be so great 50 as to cause the yarn to continue to run after 55 the yarn has been taken out of the knitting action through depressing its guide finger to disengage the yarn from the stitch wheel. This momentum results in the production of considerable slack in the yarn, and this slack may be so great 60 as to cause the yarn to continue to run after 65 the yarn has been taken out of the knitting action through depressing its guide finger to disengage the yarn from the stitch wheel. This momentum results in the production of considerable slack in the yarn, and this slack may be so great 70 as to cause the yarn to continue to run after 75 the yarn has been taken out of the knitting action through depressing its guide finger to disengage the yarn from the stitch wheel. This momentum results in the production of considerable slack in the yarn, and this slack may be so great

guide finger and the cutting and clamping device as to prevent the yarn from being reengaged with the stitch wheel to restore the same into the feeding action; or the stitch wheel may momentarily miss the yarn and thus allow the point in the needle circle at which it is desired to introduce the yarn to pass by the stitch wheel before the yarn is picked up by the stitch wheel and fed to the needles. In some striped patterns, this would result in a flaw in the pattern. 5

To overcome the aforementioned difficulty, I preferably provide one or more braking instrumentalities for the yarns, depending upon the type of yarns being used. As shown in the drawing, the braking device preferably comprises a flat 15 spring blade 46, which is disposed over the eye through which the yarn passes through the frame 5, the blade being generally L-shaped and having its upwardly extending arm 47 secured to a flange 48 extending laterally from a plate 49 which is pivotally mounted at a convenient point on the frame 5, as at 50. The plate 49 is offset laterally and oppositely to the flange 47, so as to provide a part 51 which is adapted to engage the posts or pins 25 or 25' which are carried by the crank arms 17 and 17'. The part 51 is preferably slotted, as at 52, so as to allow the plate 49 to rock on its pivot 50 responsive to rocking movement of the guide finger controlling bell-crank with which it is operatively connected. This brake construction just described is duplicated for each of the 20 yarns 6 and 8 shown in the drawing, but it is to be understood that this is not essential since the number of brake devices required will depend upon the type of yarns being used. For instance, if 25 one yarn is silk and the other is an ordinary cotton yarn, one brake device for the silk yarn may be all that is required, and the other brake may be omitted. According to the arrangement shown in the drawing, where two brake devices are employed, they are actuated alternately to clamp and release the yarns responsive to the actuation of the guide fingers 2, 2'. Since the guide fingers are preferably pattern-controlled, the brake devices may be said to be also pattern controlled, 30 having particular reference to the cam 31 which serves to actuate the instrumentalities which intermittently and alternately rock the bell crank 16, 16'. When the bell crank 16' is rocked on the pivot 14 in a counter clockwise direction as viewed 35 in Figure 1, the plate 49 is correspondingly rocked in a counter-clockwise direction, thereby moving the free end of the spring blade 46 downwardly against the upper end of the porcelain bushing 44 in the eye 43, and effectively clamping the yarn 8 40 with a firm but yieldable clamping pressure. Feeding movement of the yarn is accordingly positively discontinued, and the yarn cannot overrun so as to produce slack at any point beyond the eye 43. It will be understood that this braking 45 action on the yarn 8 occurs when the guide finger 2' is depressed to take this yarn out of knitting action. As soon as the finger 2' is elevated to put the yarn 8 back into knitting action, the elevation being effected by rocking movement of 50 the bell-crank 16' in a clockwise direction as viewed in Figure 1, the clamping blade 46 will be automatically elevated to release the yarn 8, and thereby condition the same for its normal running or feeding movement. The released condition of the clamping blade 46 is shown by the 55 clamping blade which is associated with the yarn 6, which, under the conditions illustrated, is being fed to the needles of the knitting machine by reason of the elevated position of the guide finger 60 65 70 75

2. Thus when the brake is applied to yarn 8, it is released from yarn 6, and vice versa. Operation of the brake device associated with yarn 6 is the same as just described for yarn 8, the operation being responsive to the pivotal movement of the bell-crank 16.

While the specific details have been herein shown and described, the invention is not confined thereto, as changes and alterations may be made without departing from the spirit thereof, as defined by the appended claims.

Having thus described my invention, what I claim as new and desire to secure by Letters Patent is—

15. 1. In a device of the class described, the combination with a yarn guide operable to and from yarn feeding position, of yarn clamping means interposed between the guide and the source of yarn supply for stopping the feeding movement 20 of the yarn incident to actuation of the guide to one of its positions, said yarn clamping means comprising a flat spring blade mounted for pivotal movement and positively connected with the guide and movable thereby towards and away 25 from yarn clamping position responsive to actuation of the guide.

2. In a device of the class described, a frame, a yarn guide pivotally mounted on said frame and having an eye at its free extremity for receiving a yarn therethrough, means interconnected with said yarn guide for shifting the same about its pivot to and from yarn feeding position, and yarn clamping means interposed between the guide and the source of yarn supply 30 and operable responsive to shifting movement of the guide to one of its positions, said last named means comprising a member pivotally mounted on said frame and having a part extending at one side of the pivot operatively connected with 35 the guide, and said member also having a part extending laterally therefrom at the opposite side of said pivot, and a relatively flat resilient

clamping member having one end fixedly secured to the laterally extending part aforesaid and its other end disposed for releasable clamping engagement with the yarn against the frame at a point distant from the eye in the yarn guide. 5

3. A device as claimed in claim 2, wherein the means for shifting the yarn guide includes a bell-crank lever pivotally mounted on said frame, at a distance from the pivotal member which carries the resilient clamping member, and the pivotal member being connected to one arm of the bell-crank lever by a pin-and-slot connection. 10

4. An attachment for yarn changing instrumentalities of the class described, including a shiftable yarn guide, comprising a plate adapted 15 to be pivotally mounted on a support, said plate having a laterally off-set extension at one side thereof adapted to be operatively connected with the shiftable yarn guide, and said plate also having a laterally extended flange at its opposite side, and a relatively flat spring blade member of generally L-shape having one of its arms attached to the flange aforesaid, the other of its arms being adapted for releasable clamping engagement with a yarn. 20

5. In a device of the class described, the combination with a frame, and a pattern controlled yarn guide pivotally mounted on said frame for movement to and from yarn feeding position while a portion of the yarn is disposed contiguous to the frame, of a resilient yarn clamping member also pivotally mounted on said frame for movement towards and away from the yarn, and means for positively connecting said yarn clamping member with the yarn guide aforesaid for 30 operating the yarn clamping member by the pattern control for the yarn guide, whereby to releasably clamp the yarn between the resilient clamping member and the frame incident to operation of the yarn guide to one of its positions 35 by the pattern control. 40

WILLIS A. INGALLS.
